John Darling and Barton Darling

8744 1/2 X

Letter's Patent.

The Schedule referred to in these Letters Patent and making part of the same, containing a description in the words of the said John Darling and Barton Darling themselves of their improvement in Water Wheels for moving Mill works, Machinery &c.

To all to whom these these presents shall come, be it known that we John Darling and Barton Darling both of Bellingham in the County of Norfolk and State of Massachusetts have invented a new and useful improvement in Water wheels for moving Mill works, Machinery and other things by water power, and that the following is a full and exact description of the construction and operation of the said Water wheel as invented or improved by us. We call our improved wheel, the upright perpendicular pressure wheel with spade floats. It is constructed and used in the manner hereinafter described. First, there is an upright shaft which may be either cast or wrought iron, though we prefer to have the shaft of wrought iron. The shaft should be of a length adapted to the place where it is to be used, and of the right proportioned to the weight which is to be put upon the wheel. The lower end of the shaft must be fixed to revolve upon a step or bearing. This is to be a cast iron rim connected with the lower end of the shaft by arms of cast iron. This rim and the arms may be all cast together, and if the lower end of the shaft where the arms are to be fastened were square, and a square orifice like a mortice just fitted to that part of the shaft were made in the casting of the rim where the arms meet, the rim and shaft could be easily connected. The rim and arms may also be cast in parts fitted together, and bolted to the shaft to suit the convenience of

the

the maker. The length and number of the arms, and their sizes and the thickness and depth of the rim must be adapted to the size and to the strength required on the wheel, and the depth of this rim will also, as will be seen hereafter vary to suit the speed required of the wheel, the quantity of water proposed to be used by it, and the head from which the water is to be taken. Upon the outside of this rim are to be bolted cast iron floats, two floats when connected with the rim represent precisely the threads of a screw, that is the float should be so shaped that each one when connected with & bolted to the rim would represent a portion of the thread of a large screw of which the rim would represent the body. This gives the floats themselves what we call their spiral shape. The upper end of each float or should be in the same plane with the upper edge of the rim, and the lower end of each float in the same plane with the lower edge of the rim. The floats should lap over each other somewhat. The upper end of each float should lap over or prop by the lower end of the float next to it. The distance which they pass each other on the rim may equal about twice the distance between them. The length of the floats must be governed by the number, if only one were used it must be long enough to go round the rim and lap a little at the two ends. The distance between the floats too depends upon the number to be applied to any given rim. This number and their width must be proportioned to the quantity of water to be used, the head from which it is to be drawn and the speed required of the wheel. We find the following proportions answer very well in practice, viz. with an eight feet head to have a wheel three feet in diameter including the floats, to have the depth of the rim two and a half inches, to have the number of floats i.e. the width of the floats eight inches, this wheel will revolve one hundred and fifty times per minute, and with force sufficient to drag a corn mill, if greater speed were required it might be obtained by increasing the depth of the rim or by increasing either the number

cocked coarse conform to the time in which the floats receive. The rim attached in the model to the platform represents the proper external thickness of the platform and then the cockpit might have been straight. This was considered so that the model might be as light as possible. Another and very important appendage to the wheel is the water-tight cap which keeps the water from passing upon any part of it except the floats. This cap should be of cast iron - a circular plate of sufficient thickness to be strong, equal in diameter to the exterior diameter of the rim of the wheel to which the floats are bolted, and as it lies over the wheel should not project at all over the floats. The lower side of this cap must be a circular flange to correspond as near as possible with the inside of the rim of the wheel. The flange and cap should set as close as possible to the rim of the wheel without friction to prevent the escape of water. This cap must be supported by two rods fastened to the upper side of it, which bars may be iron or wood, but the bars must be made of iron, and very fast and be supported on the upper side of the platform if that is thick enough; if the platform is not thick enough so that the cap would clear the rim of the wheel, if the bars were so placed these bars may rest on blocks secured upon the platform. The pressure of the water on the cap will keep it in its place when the wheel is in motion. Upon the platform must be placed and framed a square frame of sufficient diameter to enclose the wheel and its appendages. This frame may be of the same height with the head of water and the shaft of the wheel may at the top pass through and down in and be confined by a crossbar or breed tree crossing the top of the frame. On the top of the shaft may be fastened a coupling block, a gear or a drum to communicate the motion to work to which the wheel is to be applied. The shaft passes through the cap and must be a tight fit in the cap as it can be without screwing.

number or the width of the floats. Sudden changes will occasion the use of more water under the same head. The sum is the depth of the river, and the greater the is the number of the floats and the greater is the width of the floats. The greater is the width of the wheel which of the same diameter, and the greater is the quantity of water used under the same head; Under a given head the same power can be obtained with narrower river and narrower floats. We believe for practical purposes it will be most economical to use two ten foot diameter including the floats, but the same principles will apply to larger or smaller wheels. We think the width of the floats should equal about one fifth of the diameter of the whole wheel, and the depth of the river should be about one tenth of the same diameter. With these proportions the number of the floats may be adapted to the head of water and the speed required. We think too that when a large power is wanted it is better to have two smaller wheels constructed according to our plan than one very large one and it should not be more than four feet in diameter. The wheel should be let into a wooden platform a very little thicker than the depth of the river, so that the floats may run clear of the steep face which supports the wheel below and the bars which support the cap which will be described hereinafter. This platform must be solid and unyielding, large enough to support the floats, and the place in it where the wheel revolves must be just large enough to admit it to revolve freely and at the same time prevent the escape of the least possible quantity of water. Let this horizontal platform the wheel revolves support upon a cross bar or beech tree framed or bolted to the bottom of the platform. The shaft turns upon a top or bearing fastened to this cross bar. In this model don't have with the plate intended to represent the bottom of the floor, so the platform is not equal in thickness to the depth or width of the river of the wheel; and the cross bar supporting the wheel is represented by a bar

be a necessary fixture. The float may if that be sufficient
merely be a simple cover and the water introduced into it by a trough.
It is designed that the float should be empty except when the
wheel is in motion and that the wheel should be started by
allowing the water to run into the float. We think the wheel will
last best to be so hung that the float may be always just covered
with water, our wheel if inverted would, if enclosed in a
hollow cylinder, well answer the purpose of a very powerful
forcing pump.

Eliz. Foster Sept 1st 1834.

Drawing

To all persons to whom these presents shall come, Buxton
Darling and Eliz. Foster aforesaid would respectfully
represent, that they have contemplated the application of
the cap used in their wheels aforesaid described to keep the ex-
pulsion of the water from the axles of their said wheel to
other upright wheels for the same purpose, that is for keeping
the water from perusing upon the axles of such wheels and
impeding their motion. And they have invented such a cap
as an improvement in such upright wheels and particularly
in the cast iron wheel invented and patented by Russell
&... And the application to the said Russell wheel they
make in the following manner. The cap is a plate of cast iron
circular and just large enough to be admitted into the inside
of the said Russell wheel with a hole in the center of the cap
large enough to admit the shaft of the wheel to pass through
the said cap. The cap should be fitted as closely to the bottom of
the wheel as it can be and allow the wheel to revolve without fric-
tion, and it must be supported in its place by bolts from a
wrought base passing across the floor above the wheel.
Another application of their said cap. The said Darling have
invented

invented which is this. Let the arms of the said Russell wheel be at the top of the same rather than at the bottom, & the shaft be connected with the arms as it would be if they were at the bottom. Then place a cap of cast iron just over the top and as close to the upper edge as possible so as to keep out water from the wheel as entirely as possible & allow the wheel to revolve without friction against the cap, & the shaft of wheel passing through the cap. The cap must then be supported by a pair of wooden iron passing across the floor. The wheel so covered must then be let into the bottom of the floor in which it is to run. A circular hole is made in the bottom of the floor just large enough to admit the wheel, and the lower edge of the wheel must then be admitted into this hole just enough to prevent the escape of water through this hole except that which comes through the wheel & the orifice should fit the lower edge of the wheel as tightly as possible without friction. The wheel may then run upon a step or bearing resting on a breast tree bolted to the bottom of the floor. The wheel being so placed, the water when let into the floor will pass into the wheel and cause it to cool as it then escape through the bottom.

The said Barkings therefore claim as their invention the cap applied to their said wheel and its other applications as specified in the foregoing.

Bellingham aforesaid Oct 23rd 1834.
